(57) **CLAIM**

The ornamental design for a wire rack, as shown and described.

DESCRIPTION

FIG. 1 illustrates a perspective top view of a wire rack. FIG. 2 illustrates a front view of the wire rack of FIG. 1. FIG. 3 illustrates a back view of the wire rack of FIG. 2. FIG. 4 illustrates a left side view of the wire rack of FIGS. 1-3.

FIG. 5 illustrates a right side view of the wire rack of FIG. 4.

FIG. 6 is a top view of the wire rack of FIGS. 1-5. FIG. 7 is a bottom view of the wire rack of FIGS. 1-6; and, FIG. 8 illustrates a perspective top view of the wire rack of FIG. 1 in a stacked environmental configuration.

The broken lines are only for illustrative purposes to show visible environmental structure and form no part of the claimed invention.
